UNITED STATES PATENT OFFICE.

JOHN J. DEVINE, OF MIDDLETON, CONNECTICUT.

INKSTAND.

1,284,256.

Specification of Letters Patent. Patented Nov. 12, 1918.

Application filed May 29, 1918. Serial No. 237,273.

To all whom it may concern:

Be it known that I, JOHN J. DEVINE, a citizen of the United States, residing at Middletown, in the county of Middlesex and 5 State of Connecticut, have invented new and useful Improvements in Inkstands, of which the following is a specification.

This invention relates to an ink stand.

The object of the invention is to produce 10 an ink stand wherein the ink is arranged in a sealed receptacle, and wherein means is provided for permitting the entrance of a pen point to said receptacle so that only a determined quantity of ink will be delivered to the point and also so that the stock or holder for the pen point is held away from the ink and thus retained in a clean condition.

It is a further object of the invention to 20 produce an ink stand providing a normally closed receptacle having a pocket in the bottom thereof in which normally rests a pivoted cup or scoop, a pen directing element being arranged opposite the closed 25 entrance to the well and having means connected therewith actuated by contact with the pen holder, after the pen is inserted therethrough, for opening the entrance to the well and for swinging the cup or scoop 30 toward such entrance whereby a certain amount of ink may be delivered to the pen point.

Other objects and advantages of the improvement will present themselves as the 35 nature of the invention is better understood, reference being had to the accompanying drawings, in which—

Figure 1 is a top plan view of an ink stand constructed in accordance with this 40 invention;

Fig. 2 is a sectional view approximately on the line 2—2 of Fig. 1, showing the parts in their normal condition;

Fig. 3 is a similar sectional view but 45 showing the arrangement of parts when the pen point is inserted in the well;

Fig. 4 is a front elevation, parts being broken away and parts being in section;

Fig. 5 is a perspective view of the pen 50 directing member and the valve associated therewith; and

Fig. 6 is a similar view of the cup or scoop and the arm supporting the same.

The ink stand is generally designated by 55 the numeral 10. The base or ink contain-

ing compartment, in the showing of the drawings is round in plan, and is indicated by the numeral 11, and is preferably constructed of some transparent material, such as glass. The lower wall of the ink compartment is arranged a suitable distance above the bottom of the well 11, and this wall is indicated by the numeral 12. The well is provided with a depending pocket 13, the side walls of which being nearly 60 vertical and the bottom walls being arranged at opposite angles.

The top of the device is preferably of hollow frusto-conical formation but has an outer straight edge in the nature of a flat 70 ring which is indicated by the numeral 14, and this ring rests upon a gasket 15 on the outer or upper edge of the ink compartment 11. On the outer periphery of the ring 14 is formed a downturned flange 16 that is received in an annular depression 17 at the upper corner of the ink receptacle 11. The flange 16 is also preferably provided with an inturned bead 18 that is received in an annular groove 19 in the referred to 75 depressed portion of the ink well 11. In addition to this the flange 16 is provided with oppositely disposed and inturned pins 20 that are guided through bayonet slots 21 in the outer wall of the reduced upper portion of the ink well. By this arrangement 80 it will be noted that the dome-shaped cap 22 may be tightly secured upon the well 11 and readily removed therefrom, as for instance when ink is to be poured in the well 90 11 or when the well is to be cleaned. The dome-shaped top 22 is provided with a 95 round opening 23 that is surrounded by an inwardly extending cylindrical member or sleeve 24, and the said sleeve, from the adjacent inner edge thereof is flared outwardly as at 25, and this flared portion provides a seat for a valve that closes the opening 23, as will hereinafter be set forth in detail.

The top 22, at points away from the opening 23 is formed with upstanding members arranged in parallelism and which have their upper edges notched, thus providing a pen rack 25. On the top, between the members providing the pen rack 25 is a hood 26 that has a single opening 27 in the side thereof, the said opening being arranged in a line medially with respect to the inlet opening 23 for the inkwell.

Passing through the opening 27, and piv- 110

totally secured between the side walls of the hood 26, as at 28 is the longitudinal arm 29 of the pen directing element or means. The outer end of the arm is arranged directly over the inlet opening 23 between the dome-shaped top 22 and the ink well, and the said outer end of the arm is preferably enlarged and provided with a round periphery, so that this end of the arm I will hereinafter refer to, for convenience as the head thereof and I have designated the same by the numeral 30. The head is provided with a transverse opening, the end walls of which are straight, but the side walls of which are inclined at opposite angles. The inner side wall is indicated by the numeral 31 and is pitched or cut at a less angle than the outer side wall 32. The wall 31 thus provides what may be termed a ledge which is designed to be contacted with by the end 33 of a pen holder or stock 34 that carries a pen point 35, when the said point is to be passed through the opening 23 to receive a quantity of ink, in a manner which will presently be described. When the pen point is positioned to receive the ink the stock will rest upon a concaved surface 36 upon the upper face of the head 30.

Secured to the opposite sides of the head 30, upon the inner or lower face thereof are depending arms 37 that have secured to their outer ends a flat tubular valve 38, and this valve is designed to normally engage the valve seat 25 to close the tube 24 and the inlet opening 23.

Normally seated in the pocket 13, in the bottom wall 12 of the well 11 is a cup or scoop 39 that has connected with its bottom wall an arm 40, the said arm having its end pivotally secured, as at 41, to the top 22. If desired, and as illustrated in the drawings a spring 42 may be arranged between the top 22 and the arm 40 for normally swinging the arm downwardly and retaining the cup or scoop 29 in the pocket 13. In the event of the employment of a spring the arm 40 is provided with a suitable collar 43 to receive one end thereof and the top or cover 22 is provided with a depressed portion 44 to receive the other end of the said spring, but from experience I have found that in the majority of instances the employment of the spring is not required. Loosely connected with the arm 40 and with the inner end of the arm 29 of the pen directing means, is a link 45, the said link passing through an opening 46 in the top 22, between the said top and the hood 26.

When ink is required on a pen point, the point is inserted through the opening in the head 30 of the pen directing means. This, as previously stated, brings one end of the pen holder against the inclined wall 31 and the remainder of the end of the said pen holder against the concaved surface 36 in

the head 30, permitting the pen point 35 to pass through the opening in the head. A downward pressure on the head by the pen holder causes the valve 38 to leave its seat 25. This pressure on the pen holder also causes the lever 29 to be swung on its pivot 28 so that the end of the lever in the hood is elevated in said head and as a consequence the link connection 45 between the arm 40 of the cup or scoop 39 swings the said arm 40 upward of the bottom or top 22, bringing the cup or scoop 39 in contact with the inner wall of the top 22 and receiving therein the tube or cylinder 25 and the valve seat 26 on the end thereof. The valve 38 is likewise received in the cup or scoop, and a determined quantity of ink is thus delivered to the pen point. Because of the inclined opposite walls 31 and 32 in the opening of the head 30 the handle or stock 34 of the pen may be canted so that the pen point may be removed without contacting any of the parts of the improvement, and when so removed the parts will return to their initial position, effectively closing all openings between the top 22 and the ink receptacle.

Having thus described the invention, what is claimed as new, is:

1. In a device for the purpose set forth, a closed ink receptacle having an opening therein, a scoop in said receptacle, a pen directing element, a valve carried thereby, means between said element and scoop for normally retaining the element in one position and the valve thereof in closing position with respect to the referred to opening, and said means designed to actuate to unseat the valve and elevate the scoop toward the opening when pressure is applied on the pen directing element.

2. In a device for the purpose set forth, a closed ink well having an opening in the top thereof and a pocket in the bottom thereof, a scoop normally received in said pocket, a pen directing element on the top of the well, a valve carried thereby, means between said element and said scoop for normally retaining said element in an elevated position and the valve thereof in closing position with respect to the referred to opening, and said means designed to actuate to unseat the valve and elevate the scoop toward the opening when pressure is applied to the pen directing element.

3. In a device for the purpose set forth, a closed ink well having an opening in the top thereof, a scoop in said well, spring means for normally retaining the scoop against the bottom of the well, a pivoted pen directing element on the top of the well, a valve carried thereby, means connected to said element and said scoop for normally swinging the element to an upward position and to bring the valve thereof in closing position with respect to the referred to

opening in the top, and said means designed to actuate to unseat the valve and elevate the scoop toward the opening when a downward pressure is applied on the pen directing element.

4. In an ink well, an ink receptacle and a closure therefor having an opening therein, a scoop in said receptacle, a pin directing element carried by the closure, a valve on 10 said element, means between said element and said scoop for normally retaining the element in one position and the valve thereof in closing position with respect to the opening in the closure, and said means designed to actuate to unseat the valve and elevate the scoop toward the opening, when pressure is applied to the pen directing element.

5. In an ink well, an ink receptacle having 20 an elevated bottom provided with a pocket, the end walls of which being arranged at opposite inclinations, a scoop normally received in said pocket, a pivoted pen directing element carried by the closure, a valve 25 supported thereby, means between said element and said scoop for normally swinging one end of the element to an elevated position above the opening in the closure and to also bring the valve in closing position with 30 respect to the said opening, and said means designed to actuate to unseat the valve and elevate the scoop toward the opening when pressure is applied to the pen directing element.

6. In an ink well, an ink receptacle and a closure therefor, said receptacle having its bottom wall provided with a pocket, an arm pivotally secured to the closure, a scoop carried by said arm and normally received 40 in the pocket, said closure having an opening, a sleeve surrounding the opening and having its inner end providing a valve seat, a pen directing element pivotally secured to the closure, a valve carried thereby, connecting means between the element and the 45 arm of the scoop for normally swinging the outer end of said element to an upward position to cause the valve to engage with the seat therefor and to close the opening, and 50 said means also designed, when pressure is applied to the pen directing element, to un-

seat the valve and to elevate the scoop toward the opening in the closure.

7. In an ink well, an ink receptacle and a flanged closure therefor, said closure having an opening, an inwardly projecting sleeve surrounding said opening, said sleeve having its inner end flared to provide a valve seat, a spring influenced pivoted arm carried by the closure, a scoop on the free 55 end of said arm, a pen directing element including an arm pivotally secured to the closure and having its outer end formed with a head arranged over the opening, said head having an opening, the side walls of 60 which being arranged at opposite angles, the upper wall of which being concaved, depending members on the hood, a valve carried by said members, a link connection between the arm of the connecting member 65 and the arm of the scoop whereby to normally swing the directing member to one position to cause the valve thereof to engage the seat of the sleeve to close the opening, all as and for the purpose set forth. 70

8. In an ink well, an ink receptacle having an angular pocket in the lower wall thereof, a closure for the receptacle, an arm pivotally secured to said closure, a scoop on the end of the arm normally received in the 80 pocket of the receptacle, said closure having an opening communicating with the receptacle, an inwardly depending sleeve surrounding the same and having its outer end flared to provide a valve seat, a flanged 85 guard upon the outer face of the receptacle also surrounding said opening, an arm passing through the opening in the hood and pivoted to said hood, said arm having its outer end enlarged to provide a head, said 90 head having a transverse opening, the side walls of which being inclined and the top of said head being concaved, depending elements on the head passing through the sleeve, a valve carried by said depending 95 elements for the seat on the sleeve, and a link connection between the last mentioned arm and the arm for the scoop, all as and for the purpose set forth.

In testimony whereof I affix my signature. 100

JOHN J. DEVINE.
